UNITED STATES PATENT OFFICE.

EVERETT H. KETCHUM, OF JAMESTOWN, NEW YORK.

BLACKBOARD.

Application filed November 20, 1922. Serial No. 602,044.

To all whom it may concern:

Be it known that I, EVERETT H. KETCHUM, a citizen of the United States, residing at 15 Lakin Avenue, Jamestown, in the county 5 of Chautauqua and State of New York, have invented certain new and useful Improvements in Blackboards, of which the following, taken in connection with the accompanying drawings, is a specification.

This invention relates to an improvement 10 in blackboards and more particularly in a combination desk and blackboard which is made almost entirely of metal.

The chief object of this invention is to 15 provide a combination blackboard and desk in which the leaf or desk board is of metal, in which is a chart holder in combination with the desk board, holders for stationery and similar articles for use when the desk 20 board is positioned to function as a desk and holders for pencils, chalk, crayons, etc., for use when the desk board is positioned to function as a blackboard.

Other objects of this invention reside in 25 certain detailed improvements in the means for uniting various parts, in the formation of the desk board and in other features, as will appear from the examination of the following description made in connection 30 with the drawing which form a part thereof and in which

Fig. 1 is a front elevation of one embodiment of this invention.

Fig. 2 is a side elevation.

Fig. 3 is a longitudinal cross section showing parts in the position which they assume when the desk board is in the desk position.

Fig. 4 is a view similar to Fig. 3 showing the parts in the position they assume when 40 the desk board is in the blackboard position.

Fig. 5 is a plan view of the desk board.

Fig. 6 is an enlarged cross section of the desk board taken along the line 6-6 of Fig. 5.

Fig. 7 is an enlarged view showing the manner in which the desk board is pivoted to the support.

Fig. 8 is an enlarged transverse cross section showing guide charts mounted in the pocket of the embodiment shown in the above figures, and

Fig. 9 is an enlarged detailed view showing the manner in which the supporting legs are attached to the upright.

55 A combination desk and blackboard of the general character shown in the drawing,

which comprises upright 20 on which a desk board 21 is pivoted, and a supporting brace 22 is old and the invention here set forth consists in certain improvements therein. 60

The upright 20 comprises the legs 23, 24 connected by a lower cross piece 25 and an upper cross piece 26. For further joinder of the legs 23, 24 there is provided at the top a metal plate 27 behind the cross piece 26 and projecting below the same and fixed at each side to the legs. The lower edge of the plate 27 is bent upwardly to form a pocket 28 in which pencils, chalk, crayon, etc., are held securely so that they cannot 70 fall out even when the board is collapsed.

The sides of the plate 27 being secured to the backs of the legs 23, 24 thus form with the cross piece 26 a pocket 29 in which are placed a plurality of cards 30. On 75 these cards are various figures and drawings which will guide the child using the blackboard. One of the cards 30 is preferably left blank so that it can be used as a support on which other pictures the child may 80 desire to copy can be mounted. The upper inner ends of the legs 23, 24 are channelled to receive the edges of the cards 30 and prevent their falling out of the pocket 29 (see Fig. 8). 85

The brace 22 comprises two side pieces 31 connected near the upright 20 by a plate 32. The upper edge of the plate 32 is flanged at 33 and the lower edge is flanged at 34. The flange 34 is of sufficient width 90 so that it lies across the side pieces 31 and is secured to them. A partition 35 divides the pocket 36 formed by the flange 34 into compartments. In order to secure greater stability the side bars are also connected by 95 a cross piece 37. The upper ends of the side bars 22 are beveled as at 38 so that when the parts are open, as shown in Figures 2, 3 and 4, the bevels 38 rest against the back of the legs 23, 24. 100

The usual practice in assembling articles of this character is to employ leaf hinges of the ordinary type and to provide chains or similar means for preventing the separation of the brace from the upright beyond 105 the considered amount. In order to avoid the necessity of employing these chains the side pieces 31 are provided with the inclined faces 38 and are hinged to the legs 23 by means of flat plates 39 which may be of any 110 desired contour. The plates 39, as shown particularly in Fig. 9, are securely fastened

to the bars 31 and secured to the legs 23, 24 below the upper edges of the side pieces by pins 40 which act as pivots for the brace 22.

The board 21 is a metal plate 41 provided on each side with flanges 42 which are turned over toward the center of the plate but which terminate short of it for a purpose to be described below. In order to prevent warping or bending of the plate 41 cross depressions 43 are provided in the corners to give additional stiffness. The outer sides of the flanges 42 are at substantially right angles to the base (see Fig. 6) and when the tablet is mounted in the upright these sides 44 are parallel to the inner faces of the uprights. The tablet is pivotally mounted between the legs 23, 24 by means of the pins 40 having slotted heads 45. These pins are introduced through the sides of the legs and are threaded at 46 for secure engagement. The inner ends 47 of the pins 40 are preferably not threaded and project through apertures 48 in the sides 44. The projection of the ends 47 of the bolts is sufficient to prevent any tendency of the desk board to move out of its place.

The flanged side of the board 21 is intended to be used as a desk and in order to provide a good writing surface a blotter 30 is slipped under the flanges 42. The blotter so held will remain in position regardless of the position of the desk board 21. The pocket is intended to receive stationery and other writing materials and is, as will be observed from Fig. 3, exposed only when the desk board is down and the desk surface in position for use. In that position the rear edge 50 of the desk board bears against the lower edge of the plate 32 so that it will be held in the proper horizontal position.

The outer face 49 of the leaf 21 is suitably coated so that it may be used as a blackboard for chalk or crayons. Pins 52 in the side faces of the legs 23, 24 determine the position of the desk board 21 when it is used as a blackboard while cleats 53 on the outer face of the legs may be turned when the

desk board is in the blackboard position to prevent it from tilting forward when the lower portion of the board is being used.

50

The desk board instead of being of metal may follow the usual custom and comprise a blackboard surrounded by a wooden frame having longitudinal grooves along the inner edges which enclose the side edges of the 55 blackboard and which are of sufficient width to receive the edges of the blotter.

While certain embodiments of this invention have been shown and described, I am not to be limited thereto since it is obvious 60 that others may be made without departing from the spirit and scope of the invention as set forth in the following claims.

Having thus set forth my invention, what I claim as new and for which I desire the 65 protection of Letters Patent is:

1. A combination desk and blackboard comprising legs, a deskboard pivotally mounted upon said legs, a cross bar connecting said legs above said desk board, a plate secured to the back of said legs and said bar the lower edge of said plate extending below said cross bar and a pocket carried by said plate below said bar and above said desk board accessible in all positions of said board.

2. In a combined desk and blackboard, a desk board pivotally mounted between upright legs, said desk board being of metal treated on one face so that it can be used as 80 a blackboard, each side of said desk board being flanged away from said treated face, the outer faces of said flanges being at right angles to the base of said desk board and their edges being bent down toward but not 85 meeting said base, so that a blotter can be inserted in the spaces between the flange edges and the base.

In testimony whereof I have affixed my signature in the presence of two witnesses.

EVERETT H. KETCHUM.
